(57) **CLAIM**

The ornamental design for a golf ornament, substantially as shown and described.

DESCRIPTION

FIG. 1 is a perspective view from the left side and front of one form of a golf ornament;

FIG. 2 is a top view;

FIG. 3 is a perspective view from the left side of the golf ornament shown in FIG. 1;

FIG. 4 is a perspective view from the right side and back of the golf ornament shown in FIG. 1.

FIG. 5 is a front elevational view of a second embodiment of the central panel shown in FIGS. 1-3, shown separately for ease of illustration;

FIG. 6 is a front elevational view of a third embodiment of the central panel shown in FIGS. 1-3, shown separately for ease of illustration;

FIG. 7 is a front elevational view of a fourth embodiment of the central panel shown in FIGS. 1-3, shown separately for ease of illustration; and,

FIG. 8 is a front elevational view of a fifth embodiment of the central panel shown in FIGS. 1-3, shown separately for ease of illustration.
